TOWEL DISPENSING CABINET

Rudolph G. Birr, Lombard, and Albert C. Grunwald, River Forest, Ill., assignors to Steiner Sales Company, Salt Lake City, Utah, a corporation of Utah

Original application August 17, 1938, Serial No. 225,398. Divided and this application November 27, 1939, Serial No. 306,234

2 Claims. (Cl. 312—38)

This invention relates to improvements in dispensing cabinet constructions, and is divisional of our copending application Serial No. 225,398, filed August 17, 1938, for Towel dispensing cabinet, which has matured into Patent 2,255,609, issued September 9, 1941.

Among the objects of the invention herein is to provide means for facilitating the assembly and removal of an inner unit upon which the dispensing mechanism of the cabinet is mounted.

Another object is to provide means whereby the inner unit is, so to speak, hung on the back wall of the cabinet and supported substantially only by the back, all in a manner to facilitate assembly and disassembly of the unit.

Another object is to provide a unit made up of two side plates, each having means at front and back, the means at the rear being cooperable with sockets in the back wall to support the plates against downward, outward or lateral movement, and the means at the front being secured to corresponding front means of the outer casing, all for the purpose of simplifying the structure and facilitating disassembly of the unit, parts of which form journals for certain portions of the dispensing mechanism. Another feature is the use of a removable unit which cooperates with the bottom of the cabinet to form a supply roll-receiving chamber and which cooperates with the upper portion of the cabinet to form a soiled towel roll-receiving chamber.

Features of the invention include, the means by which the unit which supports the mechanism is detachably secured to the outer casing or within the outer casing the specific means by which the connection between the inner unit and the outer casing is made and/or facilitated; the construction of the chamber for the clean toweling by means of the parts respectively carried by the outer casing and the inner unit; the use of socket members on the back wall to receive portions of the plates to support the same; the use of a flange on the front of each plate for securing it to the corresponding side or corresponding flange of the outer casing and the specific means used for fastening the rear flange and the front flange of each plate respectively to the back and to the front of the cabinet or to a flange thereof.

Objects, features and advantages of the invention will also appear in the description of the drawings, which illustrate a preferred embodiment of the invention, and in said drawings—

Figure 1 is a vertical transverse section showing the toweling in place and the doors closed; and

Figure 2 is a horizontal section taken on line 2—2 of Figure 1 showing the manner of securing the unit in and to the outer casing.

In the drawings, numeral 1 generally designates the outer casing having sides 2 and 3 rounded at their tops and bottoms. The bottom of the casing 1 is indicated at 4. The numeral 5 indicates what is herein designated as a bottom door and this door is hinged as at 6 to the bottom 10 of the cabinet. This door closes about one-half of the front opening of the cabinet and forms part of the bottom and has at its upper end projections 8 which are engagable by latches generally designated 9. Numeral 10 indicates an upper door or cover which forms part of the top and closes about one-half of the front opening. This top door 10 laps and covers the latching projections 8 of the lower door and the heads of the latches. The lower edge 12 of the upper door 20 and the upper edge 13 of the lower door are so formed as to define when closed a dispensing slot or opening 14 downwardly through which the toweling extends.

The upper part of the lower door (see Figure 2) is inwardly, upwardly slanted as at 15, and overlying this slanted portion of the outer side is a friction-reducing plate 16 also upwardly, inwardly slanted and convergent toward the portion 15. The top of the inclined surface 15 is 30 thus brought inwardly to a non-coplanar relation with the outer surfaces of the doors.

In this embodiment of the invention there is an inner unit which is detachably secured in the outer casing and the scheme for securing this unit is a feature. The unit includes a pair of side plates (see Figures 2 and 3) respectively designated 20, 21, the vertical rear edge of each plate having a flange 22 and the back having screws 23, in this instance spot welded therein, 40 and with which openings 24 in the flanges are engaged as shown. The screws have nuts 26 to secure the flanges and therefore the plates. These flanges 22 at the back are in-turned. Each plate has also at its front vertical edge a vertically extending flange 28 which is out-turned, and each side of the outer casing has an in-turned flange 29 with which the corresponding flange of the plate overlaps. The flanges 28, 29 (see Figure 2) have openings 30, 31, the latter 50 threaded, and there are screws 32 passing through the openings to secure the flanges together as shown. There are preferably two or three screws used for each lapped pair of flanges. This connection scheme for the inner unit is a 55 feature.

On the back 35 (see Figure 2) of the outer casing near the bottom are transversely alined open-top sockets 36 (only one of which is shown) made by punching the metal inwardly. These sockets may be formed in other ways. The bottom of each flange 22 of each plate has a projection which fits into a corresponding socket. This prevents downward motion of the inner unit, and also prevents out-swing of the lower part of this detachable unit. These sockets also limit the unit at a position to facilitate registration of the openings 24 with screws 23, and do likewise for the openings 30, 31 of the front flanges 28, 29.

By the use of the sockets 36 or their equivalent in combination with some other means equivalent to 23, 24, 26, a unit which has all the dispensing and smoothing mechanism thereon, or has all of the dispensing mechanism thereon when the smoothing mechanism is not used, can be quickly attached or assembled, or after assembly be quickly detached for inspection and repair, merely by removing the nut or nuts 26 from the screws 23 and swinging the unit outwardly slightly to disengage the openings 24 from the screws and then raising it to disengage the bottoms of the flanges 22 from the sockets 36. These means 22, 36, 23 and 26 or their equivalent also act to secure the unit at a position whereat (see Figure 2) the openings 31 of the flanges 29 are registered with the openings 30 of the flanges 28, so that introduction of the screws 32 is facilitated.

In the preferred form of the invention, the dispensing mechanism (see Figure 2) is constituted by a single unit, including parts which are mounted on the two plates 20, 21 above described. This mechanism includes a pair of rollers having their axes arranged substantially in the same horizontal plane. The front roll 40 is called the measuring roll and the back roll 41 operates a soiled towel take-up roll 42 by frictional engagement with the toweling 43 thereon. Rolls 41, 40 are suitably journaled in the plates. Each roll has at one end a sprocket gear which lies at the outer side of plate 20 or at that side nearest the side wall 2 of the cabinet. These gears (see Figure 3) are designated 46, 47 and are connected by a sprocket chain 48 by which means they operate in unison so that after the toweling loop is formed and adjusted at the time of loading the cabinet, this loop is maintained by causing the same amount of soiled toweling to be taken up, as is pulled out by the user.

Associated with the measuring roll is a roll 100 known as a pinch-roll (see Figures 1 and 2). This roll is vertically movable in slots 101 of the plates 20, 21 to permit proper introduction of the towel.

In order to prevent engagement between soiled and clean toweling as the soiled towel roll increases in diameter, there is provided a guard plate 110 swingable on a pivot 111 parallel with the axes of the rolls 40, 41. This plate extends entirely across the space between the inner sides of the plates 20, 21. This guard plate is curved, and after the toweling is loaded it is swung from a rear to a forward position over the pinch-roll, as shown in Figure 2. Its movement toward the pinch-roll is limited by a lug 113 struck inwardly from plate 21 so that the guard is slightly upwardly spaced from the toweling on the pinch-roll. When in this position a concave face of

the guard is opposed to the pinch and measuring rolls.

A mechanism is carried by the removable inner unit and provides means by which space is obtained at the back of the cabinet for facilitating introduction of the toweling, for connection with the soiled towel take-up roll, and for smoothing the toweling as it approaches the take-up roll. This means includes (see Figure 2) a plate 115 mounted to swing on a horizontal axis, provided herein by means of axially alined, pivoted screws 116, one screw in each plate 20 and 21. This plate is adapted to swing forwardly to the dotted line position shown. This plate cooperates with a pair of parallel bars 118, 119, upper and lower, arranged transversely and at the back of the inner unit near the back wall of the cabinet. These bars are attached by having their ends extending through slots in the plates 20, 21. Bar 118 has its forward portion turned upwardly and rearwardly to form a smoothing edge 120, and bar 119 has its forward portion turned downwardly and rearwardly to form a smoothing edge 121. The upper edge of the plate 115 has a smoothing edge 123 cooperative with or lying between the edges 120, 121 for smoothing.

In the present case there is a normally fixed but easily removable unit upon which all of the dispensing mechanism is mounted and the chamber for the clean towel roll has a bottom formed solely by the bottom of the cabinet, and has a back and sides formed solely by parts of the unit, the back acting as a partition and being movable to permit introduction of the hand for the purpose heretofore mentioned. Thus, there is a back which separates soiled from clean toweling, which is movable forwardly and rearwardly and which, when in position to prevent introduction of the hand, is also positioned to act as a smoother for soiled, wet toweling.

We claim as our invention:

1. In a dispensing cabinet having an outer casing and an inner unit upon which a dispensing mechanism is mounted, said unit including two side plates, each plate having a flange thereon at the rear and each flange having an opening, screws carried by the back wall of the casing, each passing through one opening, nuts for the screws clamping the flanges against the back, said casing having sockets and each flange having a lower terminal portion fitting a corresponding socket to limit the unit at a position to facilitate registration of the screws with the flange openings, said casing having at the front in-turned flanges, and each plate having a front out-turned flange lapping a corresponding in-turned flange of the casing, said lapped flanges having openings in registration and screws in the openings securing the flanges together.

2. In a dispensing cabinet having an outer casing and an inner unit upon which a dispensing mechanism is mounted, said unit including two side plates, each plate having a flange thereon at the rear and each flange having an opening, screws carried by the back of the casing, each passing through one opening, nuts for the screws clamping the flanges against the back, said casing having sockets and each flange having a lower terminal portion fitting a corresponding socket to limit the unit at a position to facilitate registration of the screws with the flange openings.
